CLAIM

We claim the ornamental design for a media player, as shown and described.

DESCRIPTION

This application is also related to U.S. Design patent application Ser. No. 29/153,169, filed on Oct. 22, 2001, now U.S. Design Pat. No. D469,109.

FIG. 1 is a front perspective view of a media player showing our new design;

FIG. 2 is a front elevational view thereof;

FIG. 3 is a left side view thereof;

FIG. 4 is a right side view thereof;

FIG. 5 is a bottom view thereof;

FIG. 6 is a top view thereof; and,

FIG. 7 is a rear elevational view thereof.

The dot dash line represents an unclaimed boundary line and forms no part of the claimed design. The broken lines showing environmental boundaries and surface ornamentation are for illustrative purposes only and form no part of the claimed design.
